MACHINE FOR COATING METAL PLATES WITH METALS OR ALLOYS

Filed April 1, 1935

UNITED STATES PATENT OFFICE

2,037,503

MACHINE FOR COATING METAL PLATES
WITH METALS OR ALLOYS

Samuel Davies, Briton Ferry, Wales, assignor of
one-half to Saml. Davies: Alexander Engineering
Works Limited, Briton Ferry, Wales, a
company of Great Britain

Application April 1, 1935, Serial No. 14,161
In Great Britain April 3, 1934

3 Claims. (Cl. 91—12.5)

This invention relates to machines for coating metal plates with tin and other metals or alloys for the production, for instance, of tinned, terne and like plates, and has for its principal object to provide improved mechanism in these machines for enhancing the quality or appearance of the completed plates, economizing in coating metal or alloy and increasing the output.

According to this invention, the grease pot or hopper of these machines is fitted with a plate-wiping roll and with an associated brush-like wiper adapted to operate on the opposite face of the plate to that operated upon by the roll. There may be a single roll, or several rolls each having its associated brush-like wiper, and when the plates are to be coated on both sides there may be rolls and wipers operative on opposite sides of the plates. The rolls operate to wipe the plates free from excess coating metal and foreign matter and the brush-like wipers assist the action and keep the plates against the rolls, and very advantageous wiping is attainable without liability of the plates to buckle in their passage through the grease pot. The grease pot may be made deeper than usual for the accommodation of these wiping devices and this gives the plates a longer path in the grease pot and allows a longer time for the metal or alloy to drain off the plates. Owing to the use of the wiping means, the machines may be worked efficiently at a greater speed than heretofore usual, resulting in increase output. Such wiping devices also result in minimum expenditure of tin or other coating metal or alloy and they produce a brighter finished plate.

The wiping roll or rolls may be of larger diameter than the normal forwarding or finishing rolls to give them an appropriately greater peripheral speed than the latter rolls, and they are preferably also driven at a greater speed than the latter rolls to enhance the wiping action. The brush-like wipers may be of asbestos fibre and take the form of a pad or may simply comprise a metal plate such as a steel plate, and they may be spring-pressed or weighted to press upon the plates. When there are no plates passing through the machine or during intervals between the successive plates, the wipers may serve for wiping or cleaning the wiping roll or rolls. The forwarding or finishing rolls may be caused to exert constant pressure on the plates through sprung or other loading means.

In order to enable the invention to be readily understood, one practical construction of tinning or like machine is illustrated by way of example

in the accompanying drawing in sectional elevation.

The machine is intended for the coating of metal plates on both faces and comprises a grease-pot *a* and a shallow bath or tin-pot *b* for molten coating metal. The bath is mounted on a base or frame *c* and the grease-pot has brackets or lugs *d* by which it is bolted to the bath. The bath is of segmental shape or has a curved bottom and at the front is provided with a pair of feed rolls *e*. The latter are mounted in bearings disposed in inclined slots in brackets *f* and pressure may be applied by hand-screws *g*. The brackets *f* are referred to in the plural although only one is shown and the same applies to other parts which would obviously be duplicated in the actual machine. A flux-box *f* of hopper shape extends from just below the feed rolls *e* to the nip of a pair of tinning or coating rolls *h* in the bath *b* and is provided with lugs or brackets *f* for fixing it to the top of the bath. The bearings of the rolls *h* are mounted in inclined slots in guide brackets *k* fitted in the bath and pressure may be applied by hand screws *l*. Beyond the nip of the rolls *h* is a curved guide, or guides, such as *m* carried by the support *n* and projecting upwardly to near the nip of a pair of forwarding or finishing rolls *o* mounted near the bottom of the grease-pot.

The grease-pot extends at its lower end into the bath *b* and, like the flux box *f*, it dips below the level of the molten metal. The several rolls in the grease-pot are carried by bearing plates *p* disposed one at each side of the pot and bolted or otherwise removably secured by lug parts *r* to the top of the pot. One roll of the pair of rolls *o* aforesaid is mounted in fixed bearings in slots *s* in the plates *p* while the bearings of the other roll of the pair are movable in these slots and pressed towards the fixed bearings by double-armed levers *t* pivoted at *u* to the plates *p*. The upper arms of the levers are adjustably held at the top of the grease-pot by bolts *v* mounted in brackets *w*, either with or without the intervention of springs such as *x*. Or the levers may be yieldingly pressed against the bearings of the movable roll by means of counterweights as will be understood.

Just above this pair of rolls *o* is a wiping roll *y* of such large diameter as to have a suitably higher peripheral speed than the forwarding or finishing rolls, and this wiping roll is mounted in bearings fixed in slots *z* at one side of the bearing plates *p*. A brush *l* of asbestos or the like is bolted or otherwise secured between two plates *2* and pivotally mounted in brackets *3* disposed at the other side

of the bearing plates *p* and this brush, which may be weighted by an iron bar as at *1*, bears elastically or yieldingly at its outer end against the wiping roll *y* and wipes one face or side of the coated plates as they rise out of the nip of the rolls *o*. In addition, when a plate has passed up, the brush wipes the surface of the wiping roll. A second wiping roll *4* and brush *5* are similarly mounted above but in staggered relation and reverse fashion to the first wiping roll and brush so that the rising coated plates are wiped on their other face or side and the roll itself is similarly wiped. The wiping roll bearings may be adjustably mounted in the slots *z* if desired and they are secured by plates *6*.

Above the second wiping roll *4*, another pair of forwarding or finishing rolls *7* is mounted in bearings disposed in slots or guides such as *8* in the bearing plates *p*, the bearings of one roll being immovable whilst the bearings of the other roll are engaged by the lower arms of levers *9* pivotally mounted at *10* in the plates *p* and adjustably held at the upper end in a similar manner to the levers *t* as shown. Then above the pair of rolls *7* is another and similarly mounted pair of forwarding or finishing rolls *11* which deliver the coated and wiped plate to a cleaning machine, levers *12*, pivoted at *13*, being used in this case to maintain pressure between the rolls.

The levers *t*, *9* and *12* may be forked levers if it is desired to avoid duplication of the bolts and springs such as *v*, *x* shown in the drawing.

Furthermore, it is not essential that one of the rolls of each pair of the said forwarding or finishing rolls be elastically or yieldingly pressed against the companion roll. For instance the rolls *7* might both be mounted in fixed bearings. By resiliently mounting one of the rollers, a uniform grip is maintained and wear advantageously taken up but this is more important for the entry and exit rolls *o* and *11* as will be understood, because intermediate sets of rolls such as *7* may act principally as guides for the plates passing up.

In order to facilitate mounting of the rolls *7* and *11*, recesses *14* may be provided in the bearing plates *p* at the top, the bearings for the two sets of rolls being spaced apart by distance pieces or inserts such as *15* and the recesses *14* being closed by plates *16*.

It will be observed that owing to the mounting of the aforesaid wiping rolls and brushes and forwarding or finishing rolls in the plates *p*, these parts may be removed as a whole from the machine for adjustment or other purposes. The brackets such as *w* for the levers *t*, *9* and *12* are mounted on the plate lugs *r* so that the levers may be removed with the rolls and brushes as well.

A driving shaft such as *17* may be mounted in bearings on the top of the grease-pot or elsewhere for the purpose of imparting motion to the various rolls. This shaft is provided with a clutch or fast and loose pulleys and the shaft shown has a sprocket wheel *18* which imparts motion to one of the feed-rolls *e* by a chain *19* passing over a similar sprocket wheel *19* on such roll. Motion is transmitted to the other feed-roll by spur gearing which is left unillustrated to avoid confusion. This other feed-roll has a third sprocket wheel *20* which, by chain *21* and a further sprocket wheel *22*, imparts motion to a shaft *23* mounted in suitable bearings above the tinning rolls *h*. This shaft *23* carries a spur gear

which gears with a spur gear *24* on one of the tinning rolls and the latter are geared together like the feed rolls.

The pairs of rolls and the wiping rolls in the grease-pot are rotated by means of a spur or like wheel *25* keyed to the driving shaft. This wheel *25* transmits motion to a wheel *26* on one of the upper pair of rolls *11* and this wheel *26* meshes with a wheel *27* on one of the next pair of rolls *7*. A wheel *28* revoluble with wheel *27* next transmits motion to a wheel *29* on the wiping roll *4* and a further wheel *30* revoluble with wheel *29* meshes with a wheel *31* on the lower wiping roll *y*. Finally a wheel *32* revoluble with wheel *31* meshes with a wheel *33* on the shaft of one of the lowermost pair of rolls *o* in the grease-pot. The rolls of each pair of rolls *o*, *7* and *11* are geared together like the rolls *e* and *h*.

The rolls of the several pairs *e*, *h*, *o*, *7* and *11* have similar diameter and their driving gearing is such that they rotate at the same speed. The driving wheels for the wiping rolls *y* and *4*, however, are such that these rolls may rotate at a higher speed than the other rolls so as to improve the wiping action. As will be seen these wiping rolls rotate in the same direction as the corresponding rolls of the several pairs aforesaid.

The bath *b* for containing the molten tin or the like and the grease-pot *a* for containing the grease, generally palm-oil, are heated in any convenient or well-known manner and suitable locations of several so-called "fires" are indicated diagrammatically at *34*, *35* and *36*.

In operation, the plates to be treated are led at successive intervals to the feed rolls *e* and are fed or forwarded by them through the flux-box *i* to the tinning or coating rolls *h* which feed or forward them through the molten metal or alloy in the bath or tin-pot *b*. The guide or guides *m* deflect the plates to the nip of the lowermost pair of rolls *o* in the grease-pot and these rolls pass the plates upwardly into the grease-pot *a*. The plates first encounter the lower wiping roll *y* which, moving at a higher peripheral speed than the rolls *7*, effects a wiping action on one side of the plate assisted by the pressure of the brush *1*. Then in the further upward travel the plates next encounter the wiping roll *4* and brush *5* and finally pass to the rolls *7* and *11*, the rolls *7* drawing or guiding the plates up to the rolls *11* by which the plates are finally delivered from the grease-pot.

The metal or alloy is more or less unevenly coated on the plates when they leave the bath or tin-pot *b* and the effect of the wiping rolls is to wipe off surplus coating metal and even it up. They also clean the plate by wiping off bath impurities or "scruff". The brushes *1*, *5*, also exert a wiping action and improve the inherent wiping action of the wiping rolls by keeping the plates against the rolls. Finally, the brushes in bearing on the plates opposite to the wiping rolls exert a certain restraint which prevents any likelihood of the plates buckling between the wiping rolls and the forwarding or finishing rolls *7* due to the difference in speed of the wiping rolls and such forwarding or finishing rolls. Also there can be no buckling of the plates between the wiping rolls and the lower pair of forwarding or finishing rolls *o* because the wiping rolls rotate at a greater peripheral speed than these rolls *o*. The wiping operation and the action of the machine are thus very efficient and production may consequently be speeded up so that altogether increased output

is obtainable from one machine and a brighter finished plate obtained with minimum consumption of coating metal or alloy.

If desired one or both of the upper pairs of forwarding or finishing rolls 7, 11 may revolve in a small tinning bath or the like to increase the thickness of the coating of metal or alloy.

I claim:—

1. In a machine for coating metal plates with tin and other metals and alloys, a grease pot, a pair of forwarding or finishing rolls mounted in said grease pot, a plate-wiping roll mounted in said grease pot and of larger diameter than said forwarding or finishing rolls, a brush-like wiper mounted in said grease pot in association with said plate-wiping roll and operative on the opposite face of the metal plates to that operated upon by said plate-wiping roll, and means for driving said plate-wiping roll at a greater speed 20 of revolution than said grease-pot rolls.

2. In a machine for coating metal plates with tin and other metals and alloys, a grease pot, a plate-wiping roll mounted in said grease pot, a brush-like wiper mounted in said grease pot 25 with its operative end opposite to and on a level with said roll so as to be operative on the opposite

face of the metal plates to that operated upon by said roll, and means for constantly pressing said wiper towards said roll.

3. A metal coating machine comprising a tin-pot having a curved bottom, a flux-box and a 5 grease pot mounted in said tin-pot to dip below the surface of molten metal therein, a pair of feed rolls mounted on said tin-pot adjacent to the entrance to said flux-box, a pair of coating rolls mounted in said pot adjacent to the exit 10 of said flux-box, plate-guide means extending from the neighbourhood of said coating rolls into the lower end of said grease pot, a pair of forwarding or finishing rolls mounted in said grease pot adjacent to the forward end of said plate-guide means, a wiping roll mounted in said grease-pot above said pair of forwarding or finishing rolls, a brush-like wiper, mounted in said grease pot opposite to said plate-wiping roll and operative on the opposite face of the metal plates 15 to that operated upon by said plate-wiping roll, a second pair of forwarding or finishing rolls mounted in said grease pot above said plate-wiping roll and brush-like wiper, and means for heating said tin-pot and grease pot. 20
